UNITED STATES PATENT OFFICE.

THOMAS F. ADAMS, OF NEW YORK, N. Y.

PHOTOGRAPH-CABINET.

SPECIFICATION forming part of Letters Patent No. 606,325, dated June 28, 1898.

Application filed September 23, 1897. Serial No. 652,694. (No model.)

To all whom it may concern:

Be it known that I, THOMAS F. ADAMS, a citizen of the United States, residing in the city, county, and State of New York, have 5 invented certain new and useful Improvements in Photograph-Cabinets, of which the following is a specification.

My invention relates to a cabinet or case for the exhibition and storage of photographs, 10 and for the use of dealers in photographs, views, &c.; and the object is to provide an improved cabinet for the exhibition and storage of a large collection of photographs, so that the same may be protected and more conveniently handled than when placed in 15 albums or other contrivances in which they are at present stored or exhibited, and whereby the entire collection may be readily opened, exposed, and closed as required.

20 My invention consists of a cabinet having a stationary rear wall at the back of the storage-chamber, a side wall hinged to said rear wall, a series of picture-frames hinged directly to the inner side of said wall, and a locking device located outside of and adjacent to said cabinet for holding the side wall and frames directly supported thereby in open position.

Referring to the drawings, Figure 1 represents a front view of my improved photograph-cabinet with the door raised, exposing the inside and the frames that carry the pictures. Fig. 2 is a horizontal section thereof on the line 2 2 of Fig. 1. Fig. 3 is a similar view 35 showing the side wall thrown back and fastened against the wall with the frames in position to be inspected. Fig. 4 represents in horizontal section a double cabinet having two sets of frames, both of which are in their 40 closed or folded position.

Similar letters of reference indicate corresponding parts.

In the drawings, A represents a cabinet which may be of any dimensions suitable for 45 the purpose and may be adapted for a single set of frames, as in Figs. 1, 2, and 3, or double, as shown in Fig. 4. The front of the cabinet A is closed by a sliding or rolling door or front A', which may be raised and lowered 50 as desired. The door A' slides in ways or grooves a, formed in the side walls of the cabinet, and serves to close the case when

drawn down into closed position. The side wall A² of the cabinet A is suitably hinged to the back thereof so as to swing outwardly. 55 To this side wall A² are hinged a number of frames B in such a manner that they may be conveniently swung from one side to the other for the inspection of the photographs in the frames. For this purpose the frames B are 60 hinged by intermediate pieces or strips b to the side wall A², the joints of the hinges connecting the frames B to the strips b and the strips b to the side wall A² being placed on opposite sides of the frames, so that each one 65 of the frames can be swung to either side, thus permitting inspection of photographs placed on each side of each one of the set of frames, as will be readily understood from Fig. 3. As the frames are inspected and 70 swung to one side the succeeding frames are folded down one upon the other and lie parallel to the one next below. This result is effected by the arrangement of the hinge-joints in the manner above described and 75 by varying the length of the intermediate strips b, as shown in Fig. 3.

Each of the frames B is divided by intersecting partition-strips into spaces the size of the photographs to be framed. The upper 80 and lower sides of the horizontal dividing-strips are provided with grooves into which the photographs may be easily inserted and removed.

A suitable fastening device C is located 85 sidewise of and at such distance from the rear wall so that the side wall may be readily locked thereto when swung into open position, so as to hold the side wall in position for permitting the convenient inspection of the picture-frames. The fastening device C is 90 hinged to the wall, so as to be against the wall when not required for use.

In the modified form shown in Fig. 4 the same arrangement and construction as described above is followed, except that the cabinet is made double and has two hinged side walls which are, provided with two sets of frames B, which are swung to the right and left of the center of the cabinet. In this 100 construction each side wall is locked in open position to the wall by a separate locking device.

It will be seen that by attaching the frames

B directly to the side walls of the cabinet the construction of the device is much simplified and valuable space saved. By reason of this construction and arrangement above described the cabinet may be made comparatively shallow, so that when closed it takes up the minimum amount of wall and floor space. For the same reasons when the cabinet is opened and the frames swung out for inspection they do not project so far into the room, but are brought as close as possible to the wall. This saving of floor and wall space is a very desirable feature, as the quarters in which they are used are generally confined and more or less crowded with people.

Having thus described my invention, I claim as new and desire to secure by Letters Patent--

A cabinet for storing and exhibiting photographs, consisting of a stationary rear wall 20 at the back of the storage-chamber, a side wall hinged to the said rear wall, a series of picture-frames hinged directly to the inner side of said side wall, and a locking device located outside of and adjacent to said cabinet for holding the side wall and frames directly supported thereby in open position, substantially as set forth.

In testimony that I claim the foregoing as my invention I have signed my name in presence of two subscribing witnesses.

THOS. F. ADAMS.
